Application November 13, 1933, Serial No. 697,870
In Japan August 8, 1930

3 Claims. (Cl. 121—28)

This invention is a continuation in part of my prior application Serial Number 553,829 filed July 29, 1931 and certain parts of the subject matter of this invention will be found in the said 5 earlier application and relates to a rock drill characterized by the fact that the spool valve loosely mounted on a valve guide axis is arranged in a cylinder which is in alignment with the central line of movement of a piston hammer, and 10 that on forward stroke of the piston, an air port for shifting the valve is opened and the supply of live air to back of the piston is stopped at the same time of giving a blow to a drill steel, and thereafter an exhaust port provided in the 15 cylinder wall is opened, while on backward stroke of the piston, another air port for shifting the valve is opened and the supply of live air to front of the piston is stopped and thereafter the exhaust port provided in the cylinder wall is 20 opened.

The invention is further characterized by that the piston is provided with a ring groove, by means of which the exhaust port in the cylinder wall is communicated with either one of the air 25 ports for shifting the valve during the major time of piston strokes, so that the valve is moved with least shifting resistance.

The object of the invention is to provide a new 30 rock drill by which the pressure drop in the cylinder is avoided, energy of blow as well as number of blows is increased, vibration of the machine is reduced, loss of live air and shifting resistance of the valve are minimized, and also projecting parts of the machine are done away 35 with, all these factors combined contributing to the promotion of working capacity of the machine.

In the accompanying drawings, Fig. 1 is a vertical section of a rock drill embodying the invention, and Figs. 2 and 3 are views showing diagrammatically the action of the valve.

Referring to Fig. 1, A is a cylinder, B a valve box, D a valve guide axis, H a piston hammer, H' the cylinder bearings of the piston hammer, M a ring groove provided on the piston, G a drill steel, R a rifle bar, and S a ratchet. The valve V loosely mounted in the valve guide axis D is displaced forwards and backwards under the action of compressed air, whereby the valve opens 40 and closes respective ports provided in the valve box, and thus controls the admission and exhaustion of the air in the cylinder.

Referring to Figs. 2 and 3, H is a piston hammer, H' cylinder bearings, M a ring groove provided on the piston, R a rifle bar, f and f'

valve faces adapted to displace the valve backwards and forwards respectively, P and P' air ducts, E and E' air exhaust ports for the valve, e and e' air exhaust ducts which are in communication with spaces partitioned by the valve faces, O an auxiliary exhaust port provided in the cylinder wall for discharging air exhaust directly from the cylinder, b an air port provided with the cylinder wall for supplying air to the front face f of the valve through the duct b' to 5 push the valve backward and also for exhausting air during forward stroke of the valve and c an air port also provided in the cylinder wall for supplying air to the back face f' of the valve through the duct c' to push the valve forward and 10 also for exhausting air during backward stroke of the valve, the port O being positioned between the ports b and c.

The distance 1 between the centers of the air ports b and c is practically equal to the distance 20 l' between the centers of the cylinder bearings H', while the breadth t of the cylinder bearings is not smaller than the diameter of the ports b and c so that the both bearings can cover the 25 ports b and c at the same time. In Fig. 2, the parts are shown in the positions where, after the valve having been pushed backward, the compressed air enters in the direction of an arrow x into the chamber K' in front of the cylinder bearings H' through the air duct P', and 30 is in the instant to begin to push the piston backward. When the piston is pushed backward and the air port c is opened, the compressed air enters therethrough, thereby the rear valve face f' is 35 pushed forward and thereby the valve is displaced forward. Fig. 3 shows the position where the valve is in forward position and the piston is just reversing its direction of stroke. At this instant the compressed air enters through the 40 compressed air supplying duct a as shown in the direction of an arrow y into the chamber K in back of the cylinder bearings H' through the air duct P, thereby pushing the piston forward. When, after the piston has been pushed forward, the air port b is opened, the compressed air enters therethrough, pressing the front valve face f, and let the valve return to its original 45 position as shown in Fig. 2.

As explained above, by the reciprocating movement of the valve V and the piston hammer H attains reciprocating stroke, giving thereby a blow to the head of the drill steel G, and completing the drilling operation, as desired.

According to the invention, the arrangement of the parts being as above explained the cylinder 55

bearings H' move backward or to the right from the position shown in Fig. 2, opening the air port c and moving the valve V to the left, causing the connection between the air ducts a and P' to be interrupted, and therefore, by this means the live air is prevented from escaping through the port O, while the exhaust air contained in the front chamber K' is rapidly discharged through the passage P'-E' and also through the port O with the result that the air pressure resisting the forward stroke of the cylinder bearings H' to the left is quickly diminished, so that very quick forward stroke is subsequently attained. Further when the cylinder bearings H' move forward from the position shown in Fig. 3 or to the left into the position shown in Fig. 2, giving a blow to the drill steel and also causing the compressed air from the air port b to move the valve to the right, the connection between the air ducts a and P is stopped, and thereby the live air is prevented from escaping through the port O and air in the back chamber K is rapidly discharged through the passage P-E. On the other hand, from the fact that the cylinder bearings H', after having given a blow to the drill steel at the position shown in Fig. 2, and having moved to the left near to shunk head, firstly opens the auxiliary exhaust air port O, it is obvious that in the instant of giving the blow the port O remains closed, and thus maintains the air pressure not dropped, so that an immense energy of blow can be preserved. On the completion of the opening of the port O, the supply of the live air is stopped, and hence no live air escapes through the port O, while the piston hammer is enabled to be quickly pushed backward due to the pressure drop caused instantly by the opening of the port O. As to the above description, it is noted that when the cylinder bearings H' move to the left from the position shown in Fig. 2, the left end of the duct P' as shown is once closed, however, the same end, when the cylinder bearings H' again move to the right under the action of the compressed air in the chamber K', can be again opened. Further the most important feature of the invention is that the cylinder bearings H' are provided with a ring groove M and that the relations between the dimensions l, l' and t are before mentioned. Suppose the cylinder bearings H' are moved backward, then the ring groove M communicates the air port b and the exhaust port O at the same time when the live air supplying port c is opened, so that at the same time when the valve face f' is pushed by live air, the other valve face f is communicated to atmosphere through the ports b, M and O together with through e. Similarly, when the port b acts as live air supplying port and the valve face f is pushed by live air, the other valve face f' is communicated to atmosphere through the ports c, M and O together with through e'. This communication through the ports b, M and O or c, M and O possibly decreases the back pressure of the shifting valve and will even produce a partial vacuum at the back of the valve when the cylinder bearing of the piston hammer passes through the ports b, c and O with large speed so that it makes valve motion exceedingly sensible and greatly increases the shifting speed. In the known spool valve the valve faces are communicated to atmosphere through very small ports so that the resistance of shifting valve is very large. The invention is remarkable improvement in this point of the machine.

The advantages of the new rock drill as above explained may be enumerated as follows:

1. In the rock drill comprising a spool valve of known construction, the valve is usually mounted on the upper part of the cylinder. In the machine of such construction, difficulties are experienced in the working of the rock drill, and when in operation, especially in underground, it has numerous inconveniences due to its increased height and due to its having projecting parts. According to the invention the valve is arranged concentrically within the cylinder, so that the projecting parts of the machine are eliminated, and a smooth drill can be obtained.

2. In the known construction, the spool valve and the piston hammer are arranged one above the other, so that they work independently from each other resulting in a violent vibration of the rock drill, and also inconveniences are felt in the handling thereof. Besides, the miners are very rapidly tired in their work. According to the invention, the arrangement of the valve on the cylinder which is in alinement of the piston hammer causes the piston hammer and the valve move together on a straight line so that practically no vibrations occur in the rock drill.

3. The spool valve employed in the known rock drill, or the known heavy drifters has generally a diameter of about 25 to 38 mm., and the number of blows 1000 to 1500 per minute, and thus is inferior in this point to flapper or tubular valve which has the number of blows of 1500 to 1900 per minute. It is from this reason that the diameter of the spool valve must be increased. However, if the same is greatly increased, it results in increasing the size of the valve box mounted on the cylinder, and also corresponding inconveniences occur in the manufacture and also in the handling of the rock drill. According to the invention the valve is arranged on the cylinder itself so as to give a relatively great diameter to the valve, and by this means the valve face is naturally increased. These conditions, together with the arrangement of the ports as mentioned enables the increase of the number of blows, which in fact enables to attain the highest number of blows known in the known drill, namely 2360 per minute. Besides, it must be remarked that no loss of the live air is caused.

4. According to the invention, the displacement of the valve is much shortened corresponding to the increase of the diameter thereof.

5. From the necessity that the diameter of the valve must be made large while its displacement small in order to increase the number of blows, and for attaining a quick discharge of the air exhaust from the cylinder, it is of general practice in the known drill comprising a spool valve proper, that the exhaust from the cylinder is repeatedly passed to the valve box. The invention offers an improvement whereby a direct discharge of the exhaust from the cylinder to the atmosphere is made possible through the auxiliary exhaust air port provided in the latter. This auxiliary exhaust port rapidly reduces the back pressure of the valve at the time of its shifting through the ring groove of the piston hammer. This advantage combined with the above mentioned actions enable to remarkably increase the number of blows of the piston hammer of the invention.

6. A rock drill in which an auxiliary exhaust air port cooperates with a spool valve is known. In such construction, however, there is a defect that the live air is wasted owing to the fact that in

the instant when the piston hammer is going to give a blow, the cylinder port which is positioned behind the piston hammer is already in communication with the atmospheric air. This, of course, 5 lowers the air pressure at the instant when a blow is to be given, and consequently the efficiency is reduced. According to the invention this defect is avoided by making the direct discharge of exhaust air from the back portion of the cylinder 10 unnecessary, by making both the diameter of the valve and the exhaust port communicated with the back side of the cylinder sufficiently large, and also by making the port length considerably short. According to the invention the auxiliary 15 exhaust air port is firstly opened when the piston hammer at the forward stroke has reached to such an extent to give a blank blow, and from this fact it results that the discharge of exhaust air from the back side of the cylinder may more 20 quickly be realized, and thus the pressure is reduced more quickly, so that the air cushioning in the front of the cylinder bearings is promoted. At this instant, the communication of air ducts through the valve is inverted, and therefore there 25 is no fear of the live air escaping as waste from the auxiliary exhaust air port.

In the backward stroke of the piston hammer, the closing of the valve is completed before the opening of the auxiliary exhaust air port, and 30 therefore in this case the advantage of meeting no loss of live air is also obtained. That is to say, the auxiliary exhaust air port is firstly opened after the piston hammer has moved further under inertia. It is resulted from this that a 35 quick discharge of exhaust air is made possible, the back pressure in the case of the forward stroke of the piston hammer is reduced, while the air cushioning necessary for the backward stroke of the piston is still sufficiently kept. All 40 these conditions coming together may contribute to the increase of the efficiency and number of blows of the spool valve according to the invention.

From the foregoing, it is to be noted, above all, that the loss of live air is minimized according to 45 the invention, and it is experienced that the efficiency of the rock drill according to the invention is increased by 30 percent or doubly as compared with the heretofore known drill.

What I claim is:—

50 1. A rock drill comprising a cylinder, a piston hammer slidably mounted therein, adjacent one end thereof, a central guide axis arranged in alignment with the central line of movement of the piston hammer, a spool valve loosely mounted on the guide axis, an air port provided in the cylinder wall for supplying air to push the valve backward and also for exhausting air during forward stroke of the valve, another air port provided in the cylinder wall for supplying air to 55 push the valve forward and also for exhausting air during backward stroke of the valve, a large exhaust port provided in the cylinder wall between the air ports for exhausting air to the atmosphere from the cylinder, the ring groove acting to communicate the large exhaust port with either one of the air ports during each stroke of the piston, the distance between the centers of the air ports being practically equal to the distance between the respective centers of the cylinder bearings of the piston hammer, while the breadth of the cylinder bearings is substantially the same as the diameter of the air ports.
